DOOR TRACK

Harry S. Stevens, 30420 La Vista Verde, San Pedro, Calif.

Filed July 20, 1964, Ser. No. 80,927

Term of patent 14 years

(Cl. D13—1)

FIG. 2

FIG. 3

FIG. 4

FIGURE 1 is a perspective view of a door track showing my new design;

FIGURE 2 is an end view thereof in enlarged scale;

FIGURE 3 is a broken side elevational view showing the right-hand side of said door track with respect to FIGURE 2; and

FIGURE 4 is a bottom view thereof.

I claim:

The ornamental design for a door track, substantially as shown and described.
